CURRENT INTERRUPTING MEANS

Edmund J. Sroka, Chicago, Ill., assignor to
Schweitzer & Conrad, Inc., Chicago, Ill., a corporation of Delaware

Application July 3, 1939, Serial No. 282,633

22 Claims. (Cl. 200—117)

My invention relates, generally, to electrical protective devices, and it has particular relation to replaceable links to be used in connection with low current liquid fuses.

The primary requirements of a replaceable link for fuses adapted to interrupt low amperage (i. e., a few hundredths of an ampere) currents are, that it be capable of withstanding high tension stress and at the same time will be releasable at a predetermined low overload current, and yet retain substantially uniform characteristics while operating at any capacity below that at which it is designed to operate. In fuse devices wherein solder or similar material is used to hold two parts together and which is melted to release these parts, it is often possible to bring the current almost up to the point of operation without actually permitting the separation of the two parts, but thereby, materially altering the time-current characteristics of the circuit interrupting device. Such alteration is obviously undesirable since in effect it amounts to the enforced use of a variable characteristic device where a device of predetermined substantially constant characteristic is required. When a replaceable link is used in connection with liquid circuit interrupting devices, it is desirable that the surrounding liquid vapors or liquid will not appreciably affect the timing operation thereof. My invention provides a low current replaceable link meeting each and all of the above desirable requirements.

The object of my invention, generally stated, is to electrically interconnect terminals with a heater element, the heat from which melts a mechanical strain connection between the terminals which connection is not in circuit relationship with the terminals and which releases when a predetermined current flow is exceeded and which will not be substantially altered if this predetermined current flow is nearly but not quite reached.

Another object of my invention is the provision of terminals interconnected by a heater element the heat from which melts a mechanical connection between the terminals that is out of the electrical circuit between them.

Another object of my invention is the provision of a strain element for a circuit interrupting device which is adapted to be ruptured by heat from a heater element.

Another object of my invention is the provision of a positive mechanical connection between the terminals of a replaceable link which is capable of withstanding high tension stress and

yet can be released at a predetermined overload current.

Another object of my invention is the provision of terminals interconnected by a heater element the heat from which melts a mechanical connection between the terminals that is out of the electrical circuit therebetween and a strain wire conductor connected to one of the terminals which ruptures on a heavy overload.

10 Still another object of my invention is the provision of a low current replaceable link for liquid fuses, the time-current characteristic of which will not be affected by the surrounding liquid vapors or liquid.

15 Other objects of my invention will, in part, be obvious and, in part, appear hereinafter.

Accordingly, my invention is disclosed in the embodiments thereof shown in the accompanying drawings, and it comprises the features of construction, combination of parts, and arrangement of elements which will be exemplified in the constructions hereinafter set forth and the scope of the application of which will be indicated in the appended claims.

25 For a more complete understanding of the nature and scope of my invention, reference may be had to the following detailed description, taken in conjunction with the accompanying drawings in which:

30 Figure 1 is a vertical section through the upper end of a circuit interrupter of the liquid type illustrating the application of one embodiment of my invention thereto;

Figure 2 is a vertical sectional view of a replaceable link illustrating another embodiment of my invention;

35 Figure 3 is a view in side elevation of a replaceable link, similar to those shown in Figures 1 and 2, with a strain wire connected in series 40 circuit relationship;

Figure 4 is a vertical sectional view of a replaceable link illustrating another embodiment of my invention; and

45 Figure 5 is a vertical sectional view of a replaceable link illustrating still another embodiment of my invention.

With a view of illustrating the general nature of my invention, reference may now be had to Figure 1 of the drawings wherein the reference character 10 designates, generally, a circuit interrupter of the liquid type utilizing a replaceable link 11 which is constructed according to one embodiment of my invention. The circuit interrupter 10 comprises a glass sleeve or housing 12 with an upper terminal ferrule 13 secured

thereto by sealing alloy 14. The ferrule 13 may be closed at the top with a cap 15. An upper terminal 16 of the circuit interrupting link 11 projects through a conducting spider 17 and is secured thereto by a clamping nut 18. A lower arcing contact 19 of the circuit interrupter 10 with pins 20 projecting therefrom is supported from the lower terminal 21 of the circuit interrupting link 11. The arcing contact 19 is connected with the lower terminal (not shown) of the circuit interrupter 10 through a flexible conductor 22, the upper ends of which are gathered together and held in a tubular socket 23 secured to the lower arcing contact 19 by a screw head 24 as shown. In order to secure the immediate withdrawal of the arcing contact 19 when the circuit interrupting link 11 is operated, a strong tension spring 25 is secured at its upper end to an inwardly extending flange 26 carried in a groove 27 on the tubular socket 23. A liquid director 28 is supported by the pins 20 fitting in a groove 29 as shown. The replaceable link 11 is surrounded by a tube 30 depending from a mounting plate 31 carried from the upper ferrule 13.

The circuit interrupter 10 is of the type shown in Figure 4 of United States Patent No. 2,091,430, dated August 31, 1937, to Conrad. It differs from the Conrad circuit interrupter in that my improved replaceable link 11 is provided between the arcing terminals. Since the circuit interrupter 10 has the same general operation as the Conrad fuse and since it is shown herein only as a means of illustrating the application of my invention, its operation will not be described in detail.

The opposing terminals 16 and 21 of the replaceable link 11 are provided with an exteriorly threaded surface and may have recesses provided in the opposing ends thereof. A pair of sleeves 35 of insulating material may be screwed onto each of the terminals 16 and 21 with metal bushings 36 provided in the ends thereof, as shown. The sleeves 35 may be secured together by a thin deposit of solder 37 between the bushings 36. The solder 37 may be standard 50/50 solder or some other low melting point alloy as Wood's metal having the desired melting temperature. Coil springs 38 may be provided within the recesses 32 and 33 in the terminals 16 and 21 for supporting a conductive rod 39 therebetween. It is possible to eliminate one or both of the recesses 32 and 33 and one or both of the coil springs 38, but the preferred construction is as shown. The conductive rod 39 is provided with terminals 40 formed by spraying copper thereon and it constitutes a connection between the opposing terminals 16 and 21. The rod 39 may be made of carbon or similar conducting material with a resistance in the order of 5 to 10 ohms. Since the replaceable link 11 is primarily adapted for high potential, low current operation, this relatively high resistance of the conductive rod 39 is not particularly objectionable.

The solder deposit 37 between the bushings 36 provides a mechanical connection between the terminals 16 and 21 which is out of circuit relationship therewith. The strength of this mechanical connection remains substantially constant, not being altered by being nearly but not quite melted. It will be seen that the strength of this mechanical connection is proportional to the soldered area between the bushings 36. Since the mass of solder 37 is small, it is quickly melted when its melting temperature is reached. Ac-

cordingly, the short time rating of the replaceable link 11 is increased and the current value at which it is designed to blow is reduced.

In operation, when the current flowing through the conductive rod 39 exceeds the rated capacity of the replaceable link 11, sufficient heat will be radiated therefrom to melt the deposit of solder 37. The opposing terminals 16 and 21 may then be separated by the spring 25 while the conductive rod 39 drops out of circuit relationship therewith. The sleeves 35 of insulation material provide effective heat insulation for the rod 39, thereby making the solder 37 relatively sensitive only to the heat within the circuit interrupting link 11 and relatively only slightly sensitive to the ambient temperature. That is, the liquid vapors and liquid of the circuit interrupter 10 have little effect on the time-current characteristic of the replaceable link 11.

In Figure 2 of the drawings a replaceable link is shown generally at 45 which is of the same general construction as the link 11 except that the conductive rod 39 of link 11 is replaced with a different type of heater element. The replaceable link 45 comprises opposing terminals 46 and 47 with a pair of sleeves 48 projecting therefrom having metal bushings 49 at the juxtaposed ends thereof. The sleeves 48 are secured together by a small amount of solder 50 therebetween. Recesses may be provided in the opposing ends of the terminals 46 and 47 wherein coil springs 51 may be disposed for holding a heater element 52 therebetween. The heater element 52 comprises a wire 53 formed of suitable material such as Nichrome and wound on a core 54 of insulating material such as lava and provided with metallic terminals 55 on the ends thereof.

The operation of replaceable link 45 is analogous to that of the link 11 of Figure 1. That is, when the heat dissipated by the heater element 52 is in excess of the rated capacity of the circuit interrupting link 45, the mass of solder 50 becomes melted and allows the terminals 46 and 47 to be separated by suitable means, such as the spring 25, Figure 1.

With a view of providing what may be termed a dual functioning link embodying my invention, the construction shown in Figure 3 of the drawings may be used. A replaceable link is there shown generally at 60 comprising opposing terminals 61 and 62 with sleeves 63 projecting therefrom and provided with metal bushings 65 in the ends thereof and secured together by a mass of solder 66. The heater element provided within the sleeve 63 may be either that as shown for the link 11 in Figure 1 or for the link 45 in Figure 2. The lower terminal 62 is adapted to be secured to a terminal by a strain wire 67 which is preferably a high strength wire, such as Nichrome wire having a current carrying capacity somewhat greater than the current carrying capacity of the fuse link 60. When a short circuit occurs, the link 60 is shattered but, since this requires a slight interval of time, the circuit is opened by the fusion of the strain wire 67 which, it will be understood, takes place before the link 60 is shattered. On a relatively small overload, the solder 66 is melted first by the heat which is generated by the relatively small over-current. The bushings 65 then separate, whereupon the circuit is interrupted. The dual range of operation is thus provided on the one hand by the strain wire 67 which parts under short circuit conditions and on the other

hand by the solder between the bushings 65 which melts under relatively slight or low overload conditions and allows them to part.

Referring to Figure 4 of the drawings, another embodiment of my invention is illustrated in connection with a replaceable link designated generally at 70 comprising upper and lower terminals 71 and 72 having sleeves 73 of insulating material projecting therefrom and provided with metal bushings 74 in the ends thereof. The sleeves 73 are secured together by a deposit of solder 75 between the metal bushings 74. The sleeves 73 may be supported from the terminals 71 and 72 by pins 76 passing therethrough as shown. In order to electrically interconnect the terminals 71 and 72, a heater element 77 is provided therebetween which may be of Nichrome wire. When the current carried by the link 70 exceeds that of its rated capacity, sufficient heat will be dissipated from the heater element 77 to melt the deposit of solder 75, thereby allowing the terminals 71 and 72 to be separated. The heater element 77 will be broken when the terminals 71 and 72 are separated, since it has relatively little strength in comparison with the solder joint.

In the embodiments of the invention shown in Figures 1, 2, 3 and 4 a butt joint construction is provided between the metal bushings which are held together by a thin layer of solder. As soon as the solder is raised to its melting point, the metal bushings are immediately separated. This permits more accurate calibration of the fuse links using this butt joint construction than is the case with a lap joint as it will hereinafter appear.

In Figure 5 of the drawings still another embodiment of my invention is illustrated by a replaceable link shown generally at 80 having conductors 81 and 82 secured in the reduced sections of tubular terminal members 83 and 84. The terminal members 83 and 84 carry insulating disks 85 and 86, respectively, from which metal sleeves 87 and 88 project toward each other in telescopic relation, as shown. The sleeve 88 is somewhat smaller in diameter than sleeve 87 and projects therein a short distance. A deposit of solder 89 is provided between the interfitting portions of the sleeves 87 and 88 to secure them together. An insulating core 90 is provided between the terminal members 83 and 84 on which a heater element 81, such as Nichrome wire, may be wound to interconnect the conductors 81 and 82.

In the event that the link 80 carries more than its rated capacity, sufficient heat will be dissipated from the heater element 81 to melt the solder 89 thereby permitting the separation of the terminal members 83 and 84. The heater element 81 will be ruptured mechanically when the terminal members 83 and 84 are separated.

The embodiment of my invention illustrated by the link 80 in Figure 5 does not appear to be as satisfactory, under certain operating conditions, as the embodiments of the links shown in the preceding figures of the drawings and described hereinbefore. The type of soldered connection between the sleeves 87 and 88 does not permit the accuracy of calibration that is obtained in the other embodiments for the reason that the solder deposit 89 may become softened and allow relative movement of the sleeves 87 and 88 without actual separation thereof when the overload condition is approached and then receded from. Furthermore, since the sleeves

87 and 88 are metallic, the operation of the circuit interrupting link 80 tends to be erratic because of the fact that the metal sleeves 87 and 88 will pick up and radiate heat at various rates, depending upon the temperature of the gas or the liquid which surrounds the circuit interrupting link 80.

The embodiment of the invention shown in Figure 5 of the drawings can be advantageously used in applications where the operation is dependent not only upon heat generated as a result of current flow but also upon the ambient temperature. If the link 80 is immersed in the oil of a transformer and also connected in the circuit of the transformer, its operation would depend upon both the temperature of the oil and the current carried by the link.

When the links shown in Figures 1, 2, 4 and 5 are subjected to short circuit conditions, the heater elements thereof are ruptured and the resulting arc will cause separation of the surrounding housing or casing.

Each of the replaceable links 45 and 60, 70 and 80, shown in Figures 2, 3, 4 and 5, respectively, may be substituted for the link 11 in liquid circuit interrupter 10 of Figure 1. However, it is to be understood that my improved replaceable links are not intended to be limited in application to liquid circuit interrupters. However, my improved links are particularly applicable to liquid circuit interrupters since the surrounding liquid vapors or liquids do not appreciably affect the timing operation thereof. These links are particularly suitable for use in connection with potential transformer protection in which application the normal currents amount to only a few hundredths of an ampere. However, if found desirable, they can be used for other applications and with other types of apparatus.

Since certain further changes can be made in the foregoing constructions and different embodiments of the invention may be made without departing from the scope thereof, it is intended that all matter shown in the accompanying drawings or described hereinbefore shall be interpreted as illustrative and not in a limiting sense.

I claim as my invention:

1. In a circuit interrupter, in combination, a pair of relatively movable terminals biased for movement apart, means restraining movement apart of said terminals including a low melting point material out of electrical conducting relation between said terminals, and means for melting said material by radiated heat on flow of predetermined current between said terminals, there being an air space between said low melting point material and said melting means to retard the transfer of heat therebetween.
2. In a circuit interrupter, in combination, a pair of relatively movable terminals biased for movement apart, means restraining movement apart of said terminals including a small mass of low melting point material and means for insulating the same from at least one of said terminals so as to prevent current flow therethrough, heater means providing a current path between said terminals and adapted on flow of predetermined current therethrough to radiate sufficient heat to melt said material and thereby release said terminals for movement apart, there being an air space between said mass of low melting point material and said heater means to retard the transfer of heat therebetween.
3. In a circuit interrupter, in combination, a

pair of relatively movable terminals biased for movement apart, means restraining movement apart of said terminals including a small mass of low melting point metal and means for insulating the same from at least one of said terminals so as to prevent current flow therethrough, heater means providing a current path between said terminals and adapted on flow of predetermined current therethrough to radiate sufficient heat to melt said low melting point metal and thereby release said terminals for movement apart, there being an air space between said mass of low melting point metal and said heater means to retard the transfer of heat therebetween.

4. A replaceable link adapted to be tensioned by a spring comprising, in combination, a pair of terminals disposed to be biased apart by said spring, strain means mechanically interconnecting said terminals including a small mass of low melting point material electrically insulated from the current path between said terminals and adapted in the solid state to withstand the tension of said spring, and electric heater means electrically interconnecting said terminals and arranged and adapted to melt said low melting point material on flow of predetermined current between said terminals whereby said spring is no longer restrained and said terminals are separated thereby, there being an air space between said mass of low melting point material and said heater means to retard the transfer of heat therebetween.

5. A replaceable link comprising, in combination, opposing spaced apart separable terminals, a member carried by each of said terminals and projecting toward the opposite terminal, the ends of said members being juxtaposed and secured together with a small mass of low melting point material electrically insulated from at least one of said terminals so that no current flows therethrough, and a heater element electrically interconnecting said terminals, said link being operated when said low melting point material becomes melted by heat from said heater element.

6. A replaceable link comprising, in combination, opposing spaced apart separable terminals, a member carried by each of said terminals and projecting toward the opposite terminal, the ends of said members being juxtaposed and secured together with a small mass of low melting point material in non-electrical conducting relation to at least one of said terminals, and a heater element electrically interconnecting said terminals, said link being operated when said low melting point material becomes melted by heat from said heater element, the material forming the interconnecting means between said separable terminals, excepting said heater element, including insulating material whereby all of the current flow between said terminals takes place through said heater element.

7. A replaceable link comprising, in combination, opposing spaced apart separable terminals, a member carried by and projecting from each of said terminals toward the opposite terminal, the ends of said members being juxtaposed and secured together with a small mass of solder in non-electrical conducting relation to at least one of said terminals, and a heater element electrically interconnecting said terminals, said link being operated when said solder becomes melted by heat from said heater element.

8. A circuit interrupting link comprising, in combination, opposing spaced apart separable

terminals, a sleeve member carried by and projecting from each of said terminals toward the opposite terminal, the ends of said sleeve members being juxtaposed and secured together with a small mass of low melting point metal, and a heater element within said sleeve members electrically interconnecting said terminals, said link being operated when said low melting point metal becomes melted by heat from said heater element, and said low melting point metal being out of conducting relation between said terminals whereby the current flowing between said terminals does not flow through said low melting point metal.

15 9. A replaceable link adapted to be tensioned by a spring comprising, in combination, a pair of terminals disposed to be biased apart by said spring, strain means mechanically interconnecting said terminals including a small mass of low melting point material having a relatively large cross-sectional area and being relatively thin and electrically insulated from the current path between said terminals and adapted in the solid state to withstand the tension of said spring, and electric heater means electrically interconnecting said terminals and arranged and adapted to melt said low melting point material on flow of predetermined current between said terminals whereby said spring is no longer restrained and said terminals are separated thereby.

20 10. A replaceable link comprising, in combination, opposing spaced apart separable terminals, a member of insulating material carried by each of said terminals and projecting toward the opposing terminal with the ends thereof being juxtaposed, metal bushings provided on said juxtaposed ends and electrically insulated from said terminals by said insulating members, a small mass of solder between said bushings securing said members together, and a heater element electrically interconnecting said terminals, said link being operated when said solder becomes melted by heat from said heater element.

25 11. A replaceable link adapted to be tensioned by a spring comprising, in combination, a pair of terminals disposed to be biased apart by said spring, strain means mechanically interconnecting said terminals including a small mass of low melting point material electrically insulated from the current path between said terminals and adapted in the solid state to withstand the tension of said spring, and electric heater means electrically interconnecting said terminals and arranged and adapted to melt said low melting point material on flow of predetermined current between said terminals whereby said spring is no longer restrained and said terminals are separated thereby, said electric heater means being unattached to at least one of said terminals whereby, upon fusion of said low melting point material said terminals are mechanically free to be separated.

30 12. A replaceable link comprising, in combination, opposing spaced apart separable terminals, a recess provided in the end of at least one of said opposing terminals, sleeve members of insulating material carried by each of said terminals and projecting toward the opposing terminal with the ends thereof being juxtaposed, metal bushings on said juxtaposed ends, a small mass of solder between said bushings securing said sleeve members together, resilient means in said recess, and a heater element disposed within said sleeve members electrically interconnecting said terminals, said resilient means holding said

heater element in position to complete an electrical circuit between said terminals, and said link being operated when said solder becomes melted by heat from said heater element.

13. A renewable link comprising, in combination, opposing spaced apart separable terminals, recesses provided in the ends of each of said opposing terminals, a sleeve member of insulating material carried by each of said terminals and projecting toward the opposing terminal with the ends thereof being juxtaposed, metal bushings provided on said juxtaposed ends, a small mass of solder between said bushings securing said sleeve members together, compression spring means in said recesses, and a heater element disposed within said sleeve members electrically interconnecting said terminals, said compression spring means holding said heater element in position to complete an electrical circuit between said terminals, and said link being operated when said solder becomes melted by heat from said heater element.

14. A replaceable link comprising, in combination, opposing spaced apart separable terminals, recesses provided in opposing ends of said terminals, a sleeve member of insulating material carried by each of said terminals and projecting toward the opposing terminal with the ends thereof being juxtaposed, metal bushings provided on said juxtaposed ends, a small mass of solder between said bushings securing said sleeve members together, compression springs in said recesses, and a conductive rod disposed within said sleeve members between said compression springs electrically interconnecting said terminals, said link being operated when said solder becomes melted by heat from said conductive rod.

15. A replaceable link comprising, in combination, opposing spaced apart separable terminals, recesses provided in opposing ends of said terminals, a sleeve member of insulating material carried by each of said terminals and projecting toward the opposing terminal with the ends thereof being juxtaposed, metal bushings provided on said juxtaposed ends, a small mass of solder between said bushings securing said sleeve members together, compression springs in said recesses, a heater element comprising a conductive wire wound on a core of insulation and connected to conductive caps on the ends of said core disposed within said sleeve members between said compression springs and electrically interconnecting said terminals, said link being operated when said solder becomes melted by heat from said heater element.

16. A replaceable link adapted to be tensioned by a spring comprising, in combination, a pair of terminals disposed to be biased apart by said spring, strain means mechanically interconnecting said terminals including a small mass of low melting point material electrically insulated from the current path between said terminals and adapted in the solid state to withstand the tension of said spring, electric heater means electrically interconnecting said terminals and arranged and adapted to melt said low melting point material on flow of predetermined current between said terminals whereby said spring is no longer restrained and said terminals are separated thereby, and a fusible element in series circuit relation with said heater means adapted to blow on flow of relatively heavy overload current.

17. A replaceable link comprising, in combina-

tion, opposing spaced apart separable terminals, a sleeve member carried by each of said terminals and projecting toward the opposite terminal, the ends of said sleeve members being juxtaposed and secured together with a small mass of solder, a heater element within said sleeve members electrically interconnecting said terminals, and a strain wire connected to one of said separable terminals, said link being normally operated when said solder becomes melted by heat from said heater element, and in case of a heavy overload said link being operated by blowing of said strain wire.

18. A replaceable link comprising, in combination, opposing spaced apart separable terminals, a sleeve member of insulating material carried by each of said terminals and projecting toward the opposing terminal with the ends thereof being juxtaposed, metal bushings provided on said juxtaposed ends and electrically insulated from said terminals by said insulating members, a small mass of solder between said bushings securing said sleeve members together, and a heater element of coiled wire disposed within said sleeve members and connected to said terminals, said link being operated when said solder is melted by heat from said heater element.

19. A replaceable link comprising, in combination, opposing spaced apart separable terminals, a metal sleeve member insulated from and carried by each of said terminals and projecting toward the opposing terminal, the end of one of said metal sleeve members fitting within the other metal sleeve member, a small mass of low melting point material between the interfitting portions of said metal sleeve members for holding the same against separation, and a heater element interconnecting said terminals and disposed within said metal sleeve members, said link being operated when said low melting point material is melted by heat from said heater element.

20. In a fuse, in combination, separable terminals, and means interconnecting said terminals and preventing the same from separating including fusible means adapted to be melted by heat generated by flow of relatively high overcurrent between said terminals and means providing a butt joint construction held inseparable by a relatively thin layer of fusible metal adapted to be melted by heat generated by flow of relatively low overcurrent between said terminals, the melting either of said fusible means or of said layer of fusible metal permitting separation of said terminals.

21. In a fuse, in combination, separable terminals, and means interconnecting said terminals and preventing the same from separating including means having relatively low thermal capacity adapted to be melted only by heat generated by flow of relatively high overcurrent between said terminals and a pair of abutting metallic members having relatively high thermal capacity and secured together by a relatively thin layer of fusible metal which is adapted to be melted by heat generated by flow of relatively low overcurrent between said terminals, said low thermal capacity means and said pair of metallic members being connected in series between said terminals whereby the same are permitted to separate on melting either of said low thermal capacity means or of said layer of fusible metal.

22. In a fuse, in combination, separable terminals, and means interconnecting said terminals and preventing the same from separating includ-

ing means having relatively low thermal capacity adapted to be melted only by heat generated by flow of relatively high overcurrent between said terminals and a pair of abutting metallic members having relatively high thermal capacity and faces abutting substantially at right angles to the direction of relative movement apart of said terminals which faces are secured together by a relatively thin layer of fusible metal that is

adapted to be melted by heat generated by flow of relatively low overcurrent between said terminals, said low thermal capacity means and said pair of metallic members being connected in series between said terminals whereby the same are permitted to separate on melting either of said low thermal capacity means or of said layer of fusible metal.

EDMUND J. SROKA.
